Application August 8, 1945, Serial No. 609,633

4 Claims. (CL 273—102.2)

1

This invention relates to target shooting apparatus and more particularly to such apparatus for determining and indicating at a remote point the number of hits made on the target.

In target practice it is not only desirable to know when a target has been hit but also how many times it has been hit for a given number of rounds fired. In the past such target shooting results have been achieved by visual counting of the punctures in a target after a given period of shooting. Such a procedure is not only subject to inaccuracy but also entails considerable delay before the results of the shooting are known, and these disadvantages are accentuated with weapons of high fire power such as those which have been developed in the present era. For example, in practicing ground strafing with high fire power weapons from aircraft, especially at high altitudes, or from fast moving ground vehicles, the possible spread of the bullets is so great that all target attendants must be removed to great distances, e. g. thousands of yards, from the targets before firing may begin. Thus, the results of any particular shooting sequence cannot be known until these attendants have returned to the targets and counted the hits. This entails considerable delay with the attendant waste of manpower and equipment. The present invention enables the hits made during such practice to be determined and registered instantly at any convenient point remote from the target so that the results of the shooting can be known to the marksman almost as soon as the bullets strike the target.

It is an object of this invention to provide an electrical target structure capable of producing a sharp change in an electrical circuit characteristic each time a bullet passes through the target. It is a further object of this invention to provide apparatus to use these electrical changes to actuate timing and indicating mechanisms at some remote point.

It is a further object of this invention to provide target shooting apparatus which instantly indicates when a target has been struck by a bullet and which is capable of determining, counting and indicating the number of such hits, and of rendering such indications at any desired point remote from the target.

Another object of the present invention is to provide such target shooting apparatus which instantly indicates the number of shots registered on the target in any given period of time and which indicates this number accurately for all bullets which in flight touch any part of the target surface.

2

These and other apparent objects and advantages of this invention are obtained by the means described in the following specification and may be more readily understood by reference to the accompanying drawings wherein:

Figure 1 shows a target structure in accordance with the present invention with portions broken away to show more clearly its internal structure.

Figure 2 is the schematic wiring diagram of a target shooting apparatus embodying the present invention arranged to count the number of hits on a target of the type shown in Figure 1.

A novel automatic hit-registering target in accordance with the present invention is shown in Figure 1 with successive layers shown cut away in one corner to more clearly show its multi-layer construction. A suitably shaped sheet 90 of hard-pressed cardboard, untempered Masonite or the like, forms the base of the target and is mounted on the two supporting bars 34 and 36. This cardboard 90 is covered with an electrode layer 92 of metal screening, thin metal sheet or the like, for example, 16 mesh screen of galvanized iron, which in turn is covered by a layer 94 of light air cell material as, for example, a quarter of an inch layer of corrugated cardboard. On top of this air cell material is a thin layer 96 of hard material, for example, a sheet of hard fiber twenty thousandths of an inch thick, on top of which is placed another layer 98 of metallic screen material similar to layer 92. With the construction just described, when a metallic bullet of a length greater than the thickness of layers 94 and 96, i. e. greater than one quarter of an inch, passes through the target for a moment, it contacts both screen 98 and screen 92, thus forming an electrical connection therebetween. If the electrodes of this target, i. e. screens 92 and 98 are each connected to one line of an electrical circuit responsive to a short circuit between these lines, this circuit will react each time a bullet passes through the target. The thin hard surface layer 96 serves to prevent the wire screen 98 from being badly distorted so that it might form a permanent short-circuit connection to screen 92. The layer 94 of air cell material is provided to prevent the concussion waves in front of the bullet from bursting large holes in the back of the target and therefore in the second layer of screening 92. A layer of similar material could be used for the backing-up base 90 of the target, but such a construction is not essential. If, in spite of the hard surface layer 96, wires from the first electrode layer 98 should become permanently connected to screen

92, means may be provided, as will hereinafter be described to remove such a permanent short circuit by passing a sufficiently high current through this circuit to burn away such wire pieces bridging the gap between the two screen layers.

With a target construction such as just described, in accordance with the present invention, any number of successive hits on the target may be counted without difficulty even though these hits occur in rapid succession and even though several such bullets may pass through the same holes in the target so long as they make even a brushing contact with an edge portion of the target on their way through. Further, this novel target construction permits high speed electrical circuits to be used to determine and indicate the hits made on the targets.

Figure 2 shows one embodiment of the invention in which the number of hits on a target may be counted and indicated through a special electronic tube circuit by means of a suitable counter and indicator mechanism.

Referring to Figure 2, the two metal mesh electrode layers 92 and 98 of one of the novel targets of the type described above and generally indicated at TA-1, are connected by conductors 101 and 102, respectively, through two sets of normally closed contacts 103 and 104 of a relay RY-1 and leads 105 and 106, respectively, to the midpoint 107 of a voltage divider formed of two resistors R-1 and R-2 connected in series to the grid G-1 of an electronic tube V-1, of the grid-controlled gas-filled type frequently referred to under the trade name "Thyratron." The voltage divider formed of resistors R-1 and R-2 is connected through two conductors 108 and 109 across the output terminals 110 and 112 of a suitable direct current power supply, generally indicated at 100. Such a power supply comprises a power transformer T-1, a rectifier tube V-2, a filter choke F-1 and a filter condenser C-1 connected in a full wave rectifier circuit in the usual manner. The primary 114 of transformer T-1 is connected through a line switch S-1 to a suitable A. C. power supply line 116. An indicator lamp L-1 connected across this transformer primary 114 to indicate when the switch S-1 is closed and the circuit is energized. The cathode K-1 of the tube V-1 is heated from a heater winding 118 on the transformer T-1, and the midpoint of this winding 118 is connected to an intermediate point 120 on a voltage divider formed of two resistors R-3 and R-4 also connected across the output terminals 110 and 112 of the power supply line 100. The plate P-1 of the tube V-1 is connected through a suitable counter indicator mechanism, generally indicated at 122 and hereinafter to be described in greater detail, and a resistor R-5 to the positive terminal 110 of the power supply. The grid G-1 of the tube V-1, in addition to being connected to one electrode 98 of the target TA-1 through contact 104 of relay RY-1 is also connected to the negative terminal 112 of the power supply through a grid resistor R-6 and to its cathode K-1 through the intermediate point 120 of voltage divider R-3, R-4 through a grid condenser C-2. The counter indicator mechanism 122, shown schematically for purposes of clarity, includes a stepping electro-magnet M-1 which moves an armature member 124 against the pull of a biasing spring 126 to move a pawl member 128 along the teeth of a circular ratchet member 130 mounted on a shaft 131 to move it one increment each time the electro-magnet M-1 is

energized. This rotates shaft 131 in steps against the pull of a spiral spring 132 surrounding the shaft. A circuit breaking switch S-2 comprising two normally-closed contacts 127 and 129 is connected in series with the stepping magnet M-1 to deenergize the magnet each time that it is energized to move the pawl 128 and thus rotate the ratchet 130 through one increment of its motion. To accomplish this, the contact 127 is arranged to project under a portion of the armature member 124 so that it is moved away from contact 129 as the armature 124 moves through the last part of its motion. This switch is necessary because of the well-known characteristics of the grid-controlled, gas-filled tube V-1 whereby, after a suitable control potential is applied to its grid G-1 to cause the tube to ionize and conduct current, it continues to conduct until its anode-cathode circuit is broken for sufficient period of time to permit it to deionize. The rotation of the shaft 131 causes it to move an indicator pointer 134 along a graduated scale 136. In order to hold the ratchet 130 in the positions to which it is moved by the pawl 128 by each successive energization of the electro-magnet M-1, a latch mechanism is provided comprising a pivoted arm 138 carrying a tooth 140 which is held against the periphery of the ratchet 130 by a spring 142. This tooth 140 is shaped as shown in the drawing so as to latch the ratchet 130 in any position to which it is moved, thus preventing it from being returned to its initial position by the spiral spring 132. A release or "reset" magnet M-2 is provided to release the latch 140 and permit the indicator pointer 134 to return to its initial or "zero" position under the influence of the spiral spring 132 by attracting an armature member 144 secured to the lever 138. The release electro-magnet M-2 is connected to the positive terminal 110 of the power supply through resistor R-5 and to the negative terminal 112 of the power supply through a release or "reset" switch S-3 and a resistor R-7. The counter mechanism 122 is also provided with a limit switch S-4 comprising two normally open contacts 146 and 147 arranged to be operated by a cam 148 mounted on the shaft 131 and so positioned thereon as to close the contacts 146 and 147 when the indicator pointer 134 reaches the end of scale 136. A condenser C-3 is connected across the winding of electro-magnet M-1 to determine its operating speed and a resistance-capacity filter circuit, comprising a condenser C-4 and a resistor R-8, is connected across the circuit-breaking switch S-2. The contacts 146 and 147 of the limit switch S-4 are connected through conductors 150 and 152, respectively, in series with the solenoid 154 of the relay RY-1 across the power supply line 116. Thus the relay RY-1 is energized and its contacts are moved to their alternate position when the pointer 134 of counter 122 reaches the upper end of its scale causing cam 148 to close the circuit between contacts 146 and 147 of limit switch S-4. Energization of the relay RY-1 disconnects the electrodes 92 and 98 of target TA-1 from grid circuit of V-1 and connects these electrodes across the low voltage high current secondary 160 of a transformer T-2 whose primary 162 is connected across the supply line 116. In addition to limit switch S-4, a switch S-5 is provided also to operate relay RY-1 when desired. An indicator lamp L-2 is connected across the winding 154 of relay RY-1 to indicate when it is energized.

The operation of the novel target hit-counting

mechanism just described now is apparent. A positive potential is applied to the plate P-1 of the grid-controlled gas-filled tube V-1 from terminal 110 of the power supply 100 through resistor R-5, electro-magnet M-1 and switch S-2 of counter 122. The values of the resistors R-3 and R-4 in the voltage divider R-3, R-4 are so chosen that the potential of the intermediate point 120 is much closer to the potential of the negative terminal 112 than to the potential of the positive terminal 110 of the power supply. For example, R-3 might have a value 25 times as great as R-4, i. e. R-3 might equal 25,000 ohms and R-4 equal 1,000 ohms. With such an arrangement, a large potential, positive with respect to its cathode K-1, is applied to the plate P-1 of tube V-1 and a small potential, negative with respect to its cathode K-1, is applied to the grid G-1 of this tube. The values of the resistors R-1 and R-2 of the voltage divider R-1, R-2 are so chosen that the intermediate point 107 is considerably more positive than the intermediate point 120 of voltage divider R-3, R-4, e. g. R-1 might equal 50,000 ohms and R-2 equal 50,000 ohms.

The apparatus just described is made ready for operation by connecting it to the power supply line 116 by closure of switch S-1. At this time switch S-3 should be open and the two electrodes 92 and 98 of the target TA-1 will be connected through contacts 103, 104 of relay RY-1 to the grid circuit of tube V-1 because the winding 154 of relay RY-1 is deenergized, the pointer 134 of the counter 122 being on zero. When a bullet passes through the target TA-1, it will cause a momentary short-circuit between electrodes 92 and 98 as above described. This momentarily connects the intermediate point 107 of the voltage divider R-1, R-2 to the grid G-1 of the tube V-1, causing a potential to be applied thereto which is considerably more positive than the potential of the cathode K-1, i. e. the potential of the intermediate point 120 of the voltage divider R-3, R-4. This positive potential causes the gas-filled tube V-1 to ionize and conduct current so that its anode-cathode current flows through circuit-breaking switch S-2 and the winding of electro-magnet M-1 to energize this electro-magnet and thereby attract armature member 124 causing pawl 128 to pull the ratchet 130 through one increment of its rotation. At the same time, as it reaches the limit of its stroke, it strikes contact 127 of limit switch S-2 to open the circuit between contacts 127 and 129, thus opening the anode-cathode circuit of tube V-1, causing it to deionize and become non-conductive once more. Because the application of the positive potential to the grid G-1 of the tube V-1 which causes it to ionize is only momentary, i. e. lasting only for the period during which the bullet bridges the gap between the two electrodes 92 and 98 of target TA-1, tube V-1 will not ionize again until another positive pulse is applied to its grid G-1. This cycle of operations is repeated each time a bullet passes through the target TA-1 so that the indicator pointer 134 is stepped ahead one increment for each hit made on the target. Thus its position along the scale 136 indicates the number of hits during any predetermined period of operation. Because of the high speed of operation of such a grid-controlled, gas-filled tube as V-1, it is possible to count thousands of hits per minute if desired, a feature which is highly advantageous today because of the great fire power of modern weapons.

During operation it is possible, as above mentioned, that the two electrodes 92 and 98 of the target TA-1 may be permanently short-circuited by a piece of one of the electrodes bridging the gap to the other. Such an accident might occur if numerous bullets all passed through a small area of the target, and it would cause an incorrect indication of the number of hits on the target. To provide for such a contingency, transformer T-2 and relay RY-1 are provided to permit such accidental short circuit to be burned away. When the relay RY-1 is energized by passing a current through its winding 154, the electrodes 92 and 98 of the target TA-1 are disconnected from the grid circuit of the tube V-1 and connected across the secondary of transformer T-2 by means of the contacts 156 and 158. This connects an electrical current source of high current and low voltage between the electrodes 92 and 98 sufficient to burn away any bridging portions of the electrodes. A limit switch S-4, in the counter mechanism 122, is provided to automatically make this connection by energizing relay RY-1 each time the indicator pointer 134 reaches the end of its scale 136. Thus, in the event that a short occurs between the electrodes 92 and 98 of the target, a positive potential will be applied continuously to the grid G-1 of tube V-1, as above described, so that the pointer 134 will be automatically stepped rapidly to the end of its scale 136 to close limit switch S-4 and cause the shorting portions to be burned away. Operation of the limit switch S-4 also causes the indicator lamp L-2 to be lighted to call the operator's attention to the fact that the pointer 134 has reached the end of the scale 136 so that he can operate switch S-3 to energize the reset electro-magnet M-2 to cause the pointer 134 to be returned to its initial position under the influence of the spiral spring 132. If desired, another set of contacts, similar to contacts 146 and 147 of limit switch S-4 may be provided to be operated by the cam 148, preferably slightly later than operation of switch S-4, as a substitute for the manually operated switch S-3 to automatically return the pointer 134 to its initial position whenever it reaches the upper limit of its motion on scale 136. At the same time, the closure of such auxiliary contacts on switch S-4 may operate a dial-type counter mechanism to indicate the number of times that the pointer 134 of the mechanism 122 moves through the length of its scale, thus permitting a totalized count in the event that the number of hits in the desired period of time exceeds the number of steps in the counter mechanism 122.

With a self-registering target mechanism of the type just described, it is possible to determine instantaneously the number of hits on targets made by high fire power modern weapons without endangering personnel; thus eliminating the need for discontinuing all target practice while men enter the target area to determine the number of hits by visual examination of the targets.

As many possible embodiments may be made of the above invention and as many changes might be made in the embodiments above set forth without departing from the scope thereof, it is to be understood that all matter hereinbefore set forth or shown in the accompanying drawings is to be interpreted as illustrative only and not in a limiting sense.

I claim:

1. For use in target shooting apparatus, a tar-

get comprising an assemblage of an outer layer of electrically conductive material, an inner layer of electrically conductive material and a layer of insulating material between the conductive layers, and a rigid backing to which said assemblage of layers is bonded, said backing being of hard-pressed penetrable sheet material through which the projectile is to pass after passing through the assemblage of layers and functioning as a support for the inner layer of conductive material as the projectile passes through it.

2. The target of claim 1 in which the inner layer of electrical conductive material is metal screening.

3. In target-shooting apparatus, a target including at least two electrodes formed of spaced apart layers of electrically conductive material and adapted to be momentarily short-circuited by the passage of projectiles in flight through said target to produce electrical target-signals of short duration, substantially instantaneously operable target-signal amplifying means including a grid controlled gas-filled tube having a grid electrode and plate and cathode electrodes, means including an electrical conductor connected directly to said grid electrode to impress signals thereupon corresponding to the target-signals, circuit means for impressing a positive potential on said plate electrode, said tube being adapted to be actuated by said target-signals as received by the grid electrode, indicator means responsive to actuation of said tube to indicate the passage of one or more projectiles through said target, normally closed electrical switch means connected in said circuit means for impressing a positive potential on the plate electrode, and means responsive to firing of said tube and to actuation of said indicator means for momentarily opening said circuit means to deenergize and cut off said tube to set up the system

to receive and record the passage of the next projectile through the target.

4. In target-shooting apparatus, a target including at least two electrodes formed of spaced apart layers of electrically conductive material and adapted to be momentarily short-circuited by the passage of projectiles in flight through said target to produce electrical target-signals of short duration, substantially instantaneously operable target-signal amplifying means comprising an electronic tube having a cathode and a controlling electrode, an input circuit connected to said controlling electrode comprising continuous electrical connections between said target electrodes and said tube controlling electrode whereby said target signals are applied substantially simultaneously with their generation in the target, said input circuit having a capacitor in parallel between the controlling electrode and the cathode of said electronic tube, means for maintaining said tube in condition to respond to successive target-signals, and an indicator responsive to change of conduction of said tube to indicate the passage of one or more projectiles through said target.
